UNITED STATES PATENT OFFICE.

AINSWORTH BROWN, OF COLORADO SPRINGS, COLORADO.

WINDOW-SCREEN.

SPECIFICATION forming part of Letters Patent No. 297,667, dated April 29, 1884.

Application filed October 3, 1883. (No model.)

To all whom it may concern:

Be it known that I, AINSWORTH BROWN, a citizen of the United States, residing at Colorado Springs, in the county of El Paso and 5 State of Colorado, have invented a new and useful Window-Screen, of which the following is a specification, reference being had to the accompanying drawings.

This invention relates to fasteners for that 10 class of window screens or shades which are mounted upon spring-rollers, and in which no special separate provision is made for retaining the edges of the screens in contact with the sides of the window-frame; and it has for 15 its object to provide a simple and useful device for the purpose stated, which may be produced at a small expense, as will be herein-after described, and particularly pointed out in the claim.

20 In the drawings hereto annexed, Figure 1 is a perspective view of my invention, showing the same applied to a window-frame in position for operation. Fig. 2 is a horizontal sectional view, and Fig. 3 is a vertical sectional view.

25 The same letters refer to the same parts in all the figures.

A in the drawings refers to the base-plate, which is provided with upwardly and downwardly projecting arms B B, having perforations C, to receive the nails, screws, or other fastenings by means of which the device is secured to the window-frame.

At the sides of the arms B B the plate A is provided with forwardly-bent arms D D and 35 E E, between the former of which is secured a laterally-projecting flat spring, F.

Between the arms E E is pivoted a lever, G, adapted to bear against the flat spring F and force the inner end of the latter downwardly against the face-plate.

From the foregoing description, taken in connection with the drawings hereto annexed, the operation and advantages of my invention will be readily understood.

45 By this device the retention of the shade is accomplished by means of friction only, and without possibility of injury to the window-frame.

I claim as my invention—

50 The combination of a base-plate, A, having forwardly-bent arms D D and E E, the laterally-projecting flat spring F, secured between the arms D D, and forced outward from the body-plate A by its own tension, and the cam-lever G, pivoted between the arms E E, and adapted to force the end of the spring F into contact with the base-plate; as and for the purpose herein set forth.

55 In testimony that I claim the foregoing as my own I have hereto affixed my signature in presence of two witnesses.

AINSWORTH BROWN.
